CLAIM

The ornamental design for a storage container, as shown and described.

DESCRIPTION

FIG. 1 is a perspective view of a storage container of the present invention showing our new design;

FIG. 2 is a perspective view of a storage container of the present invention showing our design with the cap portion removed from the body of the storage container;

FIG. 3 is a top view thereof;

FIG. 4 is a bottom view thereof; and,

FIG. 5 is a side view.
